UNITED STATES PATENT OFFICE.

JOHN SUTHERLAND, OF SPRINGER, NEW MEXICO.

CULINARY IMPLEMENT.

1,262,404.

Specification of Letters Patent.

Patented Apr. 9, 1918.

Application filed February 5, 1917. Serial No. 146,823.

To all whom it may concern:

Be it known that I, JOHN SUTHERLAND, a citizen of the United States, residing at Springer, in the county of Colfax and State 5 of New Mexico, have invented certain new and useful Improvements in Culinary Implements; and I do hereby declare the following to be a full, clear, and exact description of the invention, such as will enable 10 others skilled in the art to which it appertains to make and use the same.

This invention relates to tools, and more particularly to culinary implements of the type designed to be used for the removal of 15 closures, caps, tops, or the like of various kinds of containers.

It is a particular object of the present invention to provide a substantial, inexpensive and practical device, whereby various covers, caps, closures, etc., may be readily, 20 quickly and easily removed from the containers on which they may be mounted, and a further object of the invention is to provide means for the ready adjustment of the 25 implement so that it may be applied to the effective opening of covers, tops, etc., of cans, bottles, or containers of various diameters and sizes.

A further object of the invention is to 30 provide a combination tool or culinary implement in which the parts may be readily detached for renewal or replacement and so that they may be cleaned and kept in a good sanitary condition.

35 A further object of the present invention is to provide a tool having an adjustable member therein which may be utilized for the removal of tops or closures of cans by the cutting or severing thereof from the top 40 end of the can to be opened, and which member is also provided for use in the opening or removal of various clamps, closures, or other devices which are frictionally secured in position upon containers which are 45 to be opened.

With these and other objects in view the invention consists of the novel tool, the combination of parts, details of construction, and arrangement of the elements as more 50 particularly hereinafter described and shown in the accompanying drawings, in which:

55 Figure 1 is a plan view of the improved tool showing the opener member adjusted in an intermediate position along the length of the tool.

Fig. 2 is an edge view of the implement.

Fig. 3 is an end view looking toward the upper end of Fig. 1.

Fig. 4 is a section on line 4—4 of Fig. 2.

Fig. 5 is a section on line 5—5 of Fig. 2 60 looking in the direction of the arrows.

Fig. 6 is a plan view of the main frame or body of the implement, and

Fig. 7 is a detail view showing in edge elevation the adjustable closure or top 65 removing member with a portion of its actuating screw connected thereto.

In the form of my invention herein disclosed, 1 represents a substantial body portion of suitable length and width and having 70 a sufficient thickness to be rigid and stiff and adapted to withstand the strains to which it will be subjected in the removal of various closures from containers which are to be opened, and, as shown in Fig. 6, the body 75 portion consists of a substantially oblong, narrow element which is longitudinally slotted from one face to the other to form a groove or channel 1^a extending substantially the length of the body member 1, and which 80 is widened at its intermediate portion 1^b. Slidably adjustable along the forward and reduced end of the body 1 there is provided a transverse plate or opener member 3 which, as shown in Fig. 5, is notched on its opposite edges at 3^a to snugly fit upon the body portion 1 and move longitudinally along the same, the plate 3 standing perpendicularly from the sides of the body 1 and projecting 85 from its upper and lower surfaces. One end 90 or projecting side of the member 3 is provided with a cutting edge at 3^b which is shown as curved and extending from adjacent one surface of the body 1 upwardly and outwardly, the curved edge providing 95 for the ready cutting of a metallic or other top of a can or the like which is to be opened. When the device is applied to the can in such manner that a pivot or fulcrum point 10 provided in the smaller end of the 100 body 1 is forced through the metallic can top or other closure to be opened, the plate 3 is turned in an arc about the fulcrum or pivot point as a center.

For the purpose of providing for the practical and ready opening of cans having metallic covers which are severed by the cutter or member 3 when this is rotated in an arc about the pivot point 10 and when these covers are of various diameters, the member 110 3 is adapted to be shifted longitudinally along the channel 1^a so as to bring its cut-

ting edge 3^b just within the circumference of the can and adjacent the outer edge of the can top when the point 10 is punched into the central portion of the top to form the center about which the implement may be swung to cause the cutter edge 3^b to sever the material in an arc about the center. In the present form of the invention this adjustment of the member 3 with relation to the pivotal point 10 is secured through means of a screw 4 which is rigidly secured in the central portion of the member 3 and extends longitudinally and centrally through and within the channel 1^a of the body portion 1 of the implement, the screw being provided with a nut 6 which is of diameter slightly less than the transversely widened portion 1^b of the slot or channel 1^a in the body member and is adapted to be turned therein on the screw and is held by the shoulders of the transverse slot 1^b against longitudinal movement with the screw, the resulting action being that the screw 4 is projected forwardly or rearwardly along the channel 1^a carrying the closure opening device 3 with it to the desired point with relation to the pivot point 10 at the end of the member 1. The lower or broadened end of the body member 1 is provided with covering sections or cheek plates 2-2 which may be riveted or otherwise secured to the body member 1 to give a convenient gripping portion to the implement, and also for the purpose of closing the lower end of the channel 1^a in the thickened or widened portion of the body 1. In assembling or detaching the device with the plates 2 removed from one or the other of the sides of the body 1, the screw with its opening member 3 thereon is adjusted in the lower portion of the slot 1^a with the member 3 alined with the transverse or widened portion 1^b of the slot 1^a so that the recesses 3^a in the opposite edges of the opener member 3 are alined with the shoulders of the channel at 1^b, thus permitting the member 3 to be slid forwardly in guided and mounted relation on the upper end of the body member 1, the screw lying within the channel 1^a. When the opener member 3 has been advanced toward its upper limit of movement in the channel 1^a the nut 6 is then dropped into the opening or pocket 1^b provided therefor and the lower end of the screw is then drawn backwardly into the nut and the latter turned to engage the threads thereof after which the longitudinal position of the screw 4 with its opener member or transverse head 3 may be adjusted at any desired position longitudinally along the upper and contracted portion of the member 1. The screw and the nut device therefore may be removed at any time desired when the handles 2, or one of them, are removed from position upon the body 1.

To enable the implement to be utilized for the removal of covers, caps, or closures which are frictionally locked in position upon containers, one end of the transverse member 3 carried by the screw is shown in Figs. 2 and 7 as provided with an upwardly and inwardly turned hook portion 3^c which may be applied beneath the lower edge of the cap or other frictional closure to be removed, and in order to prevent unnecessarily marring or injuring covers of jars, cans, glasses, or the like which are frictionally held in position on the containers, it is desirable that the lifting claw or member 3^c be adjustable relatively to the handle 1 of the implement so that in removing covers of relatively large diameter the claw can be retracted from the outer end of the implement to a position, for instance as shown in Figs. 1 and 2, and then when the face of the body member 1 adjacent to the hook or claw-like portion of the opener 3 is applied to the top face of the cover and the hook 3^c adjusted inwardly against the lower edge of the cover or clamping element, when pressure is applied to the grip portion of the handle the large area of the latter resting upon the handle serves to enable the upward pressure of the claw 3^c against the edge of the cover without indenting or marring the top surface of the cover in any substantial degree.

To give further utility to the present implement the grip portion of the handle 1 is provided at one of its corners with a recess or pocket 1^e into which there may be inserted a suitable cutter as a disk 11 which may be utilized to cut glass, and reserve or extra cutters are adapted to be contained in a chamber or pocket 11^a formed for such purpose in a suitable portion of the body member 1, this pocket being covered by the side or cheek plates 2-2 of the implement when these are mounted in position.

It is understood that the closure removing member 3 may be of any suitable form and material and may be so connected to its carrying or actuating screw 4 as to provide for removal therefrom and replacement when the cutting edge 3^b or the cap engaging hook portion 3^c thereof become injured or dull, and further it is understood that the grip forming side pieces or cheek plates 2-2 may be applied to the main body portion 1 in any suitable manner so as to provide for the ready removal and reattachment of these members to the body 1 so as to permit the ready mounting and detaching of the screw with its nut, and also to provide ready access to extra cutters 11 which may be placed in the pocket 11^a provided therefor.

From the foregoing it will be seen that I have provided a ready and simple means for the adjustment of the member 3 which may be utilized to remove covers of differ-

ent types from containers of various size, and particularly I have provided means for positively and firmly holding the closure removing member 3 at any of its respective 5 positions along the handle 1 to which it may be desired to adjust it to enable its use for the removal of closures of different sizes from their respective containers. It is understood that various modifications, alterations, and changes in the structure of the 10 implement may be resorted to within the spirit of the invention and limitation of the appended claims.

What I claim is:

15 1. A closure removing device comprising a flat body portion slotted substantially from end to end and having attached handle plates at one end and a screw movable longitudinally in and wholly within 20 said slot and carrying a cutter projecting perpendicularly from one side of the body, said cutter supporting the screw at one end on the body, the handle plates covering and supporting the other end of the screw, the 25 walls of the slot laterally notched and a nut of said screw projecting into the opposite notches.

2. A tool comprising a longitudinally slotted flat body, the slot widened on each 30 side at about midway its length, handle plates at one end of the body, a nut in the widened part of the slot, a screw between

the mouths of the slot movable by the nut longitudinally in the slot and supported at one end in said handle, a cutter secured on 35 the other end of the screw, projecting from and sliding on said body, the nut removable from the screw when the latter is fully advanced and the screw being removable from the body when the handle plates are detached and the cutter registers with the widened part of the slot.

3. A can opener comprising a flat longitudinally slotted body, having a punch at one end, the slot being laterally widened 45 midway its ends; a nut fitting the widened portion of the slot and of greater diameter than the thickness of the body, a screw disposed lengthwise in the slot, and between the faces of said body and threaded in the 50 nut, an edged blade fixed on the screw, and handle plates secured to said body and extending from one side of the nut to the end of the body to cover and support the adjacent end of the screw, the nut being exposed 55 on opposite sides of the handle to facilitate operation by the fingers of the hand in which the tool is held.

In testimony whereof I affix my signature in presence of two witnesses.

JOHN SUTHERLAND.

Witnesses:
